UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

SAFETY DEVICE FOR ADDRESSING-MACHINES.

1,184,433.

Specification of Letters Patent. Patented May 23, 1916.

Application filed March 23, 1912. Serial No. 685,814.

To all whom it may concern:

Be it known that I, JOSEPH S. DUNCAN, a citizen of the United States, residing at Chicago, in the county of Cook and State 5 of Illinois, have invented certain new and useful Improvements in Safety Devices for Addressing-Machines, of which the following is a specification.

This invention relates to addressing machines in general and more particularly to safety devices therefor, designed to prevent the fingers of the operator from becoming crushed or pinched beneath the platen during the operation of the machine.

15 One of the primary objects of the present invention is the provision of a safety device adapted to stop the operative movement of the platen arm and the platen carried thereby in case the fingers, or some 20 other foreign object, become accidentally caught beneath the platen on its downward or printing stroke and to provide a device of this character which will be simple in construction and delicate and reliable in 25 operation.

The invention will be best understood by reference to the following description when considered in connection with the accompanying drawings illustrating one preferred 30 embodiment thereof.

Referring to the drawings—Figure 1 is a plan view of so much of the addressing machine, as is necessary to the understanding of my present invention, equipped with 35 my improved safety device; Fig. 2 is a side elevation of the mechanism shown in Fig. 1; Fig. 3 is a front elevation of the mechanism shown in Figs. 1 and 2; Fig. 4 is a sectional view taken substantially on the 40 line 4—4 of Fig. 1; and Fig. 5 is a sectional view taken on the line 5—5 of Fig. 1.

On the drawings in which like numeral references designate corresponding parts in the several figures, 11 designates the platen 45 arm carried by a horizontal shaft 12 which is mounted in the frame 13 in a well known manner. The platen 14 carried on the free end of the platen arm 11 is provided with a facing 15 of rubber, felt or other suitable 50 material and is fastened in a frame 16 secured on the end of the platen arm by a screw-bolt 17. The envelops, or other work to be printed, are placed in succession upon the table or plate 18 pivoted to the frame 55 of the machine at 19. The printing device

and the inking ribbon (not shown) are fed to printing position by the usual mechanism and the platen arm is oscillated about the shaft 12 to bring the platen 14 into engagement with the work positioned on the table 60 18 by suitable mechanism which it is unnecessary to describe in this application. The platen is adjusted on the platen arm by adjusting screws 21 in the usual manner. All of the aforementioned mechanism and 65 its method of operation is well known to those skilled in the art and, therefore, it is believed that the foregoing brief reference to these parts will be sufficient. In this particular type of machine the envelops, or 70 other matter to be printed, are placed in printing position beneath the platen and withdrawn therefrom, after the printing, by hand and it sometimes happens that the operator's fingers are caught beneath the 75 platen on its downward stroke. Since the platen is lowered into printing position with considerable force, it will be obvious that the operator's fingers may be pinched beneath the platen very seriously. 80

My present invention, which is designed to stop the downward movement of the platen in case the fingers of the operator become accidentally caught beneath the platen, is constructed in the following 85 manner: A tripper yoke 22 is pivotally mounted upon the ears 23 projecting upwardly and rearwardly from the platen frame 16, said yoke having forwardly extending arms 24 and 25 and an upwardly 90 extending arm 26 to which one end of the connecting link 27 is attached. The tripper proper consists of a transversely extending bar 28 suspended in front of the platen by arms 29 and 30 pivotally mounted on the 95 yoke arms 24 and 25. The rear end of the tripper arm 30 is extended rearwardly of its pivotal connection with the arm 25 to form the extension 31 and, a light coiled spring 32 is positioned beneath this extension 31 and the arm 25, to normally hold the tripper 100 28 against the forward face of the platen, in the position shown in Figs. 2 and 4. It will be obvious, therefore, that a pivotal movement of the tripper on its yoke is permitted, so that in case the operator's fingers are caught beneath the platen they may be withdrawn without being scraped or injured by the tripper, since the tripper bar will swing 105 outwardly away from the platen as the 110

2

fingers are jerked away. The spring 32 will normally retain the tripper bar close to the platen as shown. The pivoted mounting of the tripper yoke on the ears 23 permits the 5 yoke and the tripper mounted thereon to swing as a whole on the yoke pivots which movement, it will be apparent, permits the tripper bar 28 to move up and down relatively to the platen. Should the fingers of 10 the operator be positioned beneath the platen on its downward movement they will first be struck by the tripper bar 28 which will move upwardly relatively to the platen thereby swinging the tripper yoke on its 15 pivot and imparting a rearward movement to the connecting rod 27 which, as before stated, is attached at one end to the upwardly projecting yoke ear 26. The other end of the rod 27 rests in a socket formed in 20 a downwardly projecting arm 33 secured on a short rock shaft 34 which is mounted in the platen arm 11 and has fixed to its outer end a ratchet dog 35. A coiled spring 36 attached at one end to an ear 37 projecting 25 from the rod 27 and at its other end to a boss 38 projecting from the arm 33 holds the rod 27 and the arm 33 in coöperative relation and prevents the end of the rod from being withdrawn from the socket in 30 the arm 33. A second tension spring 39 is secured at one end to a boss 40 projecting from the opposite side of the arm 33 and at its other end to a pin 41 fixed to the platen arm. This spring normally tends to draw 35 the arm 33 forward so that the tripper will be yieldingly held in the normal position shown in the drawings and the ratchet dog 35 will be held in elevated position against the stop pin 42. A ratchet bar 43 is pivot 40 ally connected to the main frame 13 at 44 and projects forwardly and adjacent the arm 11 just beneath the ratchet dog 35. The ratchet bar is provided near its free end with ratchet teeth 45 forming in effect an un- 45 yielding stop with which the dog 35 is adapted to engage, thereby locking the platen arm against further forward and downward movement about the shaft 12 and preventing the platen from being depressed 50 against the table 18.

The operation of my device is briefly as follows: During the normal operation of the machine the parts are held in the position shown in Fig. 2 by the contraction 55 spring 39 so that the dog 35 travels idly above the ratchet teeth on the bar 43 and the platen is depressed into printing position at each oscillation of the platen arm. Should the fingers of the operator, however, 60 be accidentally positioned in the path of the downwardly moving platen they will be engaged first by the tripper bar 28 by reason of the inclined position of the fingers occasioned by the inclination of the table 18. 65 The tripper and the yoke upon which it is

mounted are quite delicately mounted so that as soon as the tripper bar engages the fingers the tripper is raised relatively to the platen, the yoke is oscillated on its pivot, whereupon the connecting rod 27 pushes rearwardly upon the arm 33 to rock the shaft 34 and depress the forward end of the ratchet dog 35 into engagement with one of the ratchet teeth on the bar 43. Since the bar 43 is fixed to the main frame 13 the interlocking engagement of the ratchet dog 35 with the bar prevents further forward and downward movement of the platen arm. The downward stroke of the platen is, therefore, immediately arrested and the fingers of the operator are saved from serious injury. The pivotal mounting of the tripper on its yoke permits the tripper to swing outwardly as the fingers are withdrawn, thereby obviating any abrasion of the fingers such as might be occasioned by scraping across the edge of the tripper bar 28. It will thus be seen that the movement of the platen is arrested immediately upon contact of the tripper with any foreign object beneath the platen and that the platen will be locked against further movement until the object has been withdrawn and the ratchet dog has been released from engagement with the ratchet bar 43.

It is believed that my invention and its mode of operation will be understood from the foregoing without further description and, while I have shown and described a preferred embodiment of my invention, it will be obvious that various changes in the construction and arrangement of the mechanical elements or their equivalents may be resorted to without departing from the spirit of the invention or sacrificing any of the material advantages thereof.

I claim:

1. In a printing machine, a platen having a reciprocatory printing stroke, and means actuated by an obstruction in the path of the platen to automatically instantaneously and positively stop the printing stroke of the platen.

2. In a printing machine, a platen having a reciprocatory printing stroke, and means to automatically instantaneously and positively stop the printing stroke of the platen, said means including a tripper carried by the platen and disposed for engagement with an obstruction in the path of the platen.

3. In an addressing machine, a swinging platen arm, a platen carried thereby, a stop member having ratchet teeth, a dog carried by the platen arm for engagement with the ratchet teeth of the stop member, means to hold the dog out of coöperative relation with the ratchet teeth of the stop member, a tripper carried by the platen and disposed for engagement with an obstruction in the

path of the tripper, and means controlled by the tripper for moving the dog into cooperative relation with the ratchet teeth to stop the printing stroke of the platen arm.

5. 4. In a safety device for addressing machines, the combination of a platen arm, a tripper carried thereby, a ratchet bar disposed adjacent the platen arm, a dog mounted on said arm, and connections between said 10 dog and said tripper whereby upon actuation of the tripper the dog is engaged with the ratchet bar to stop the movement of said platen arm.

5. In a safety device for addressing machines, the combination of a platen arm, a platen carried thereby, a tripper carried by said arm adjacent the platen, a stop, a dog pivotally mounted on said platen arm, and connections between said dog and said 20 tripper whereby upon actuation of the tripper the dog will be brought into operative engagement with said stop to prevent further movement of the platen arm.

6. In a safety device for addressing machines, the combination of a platen arm, a platen carried thereby, a tripper pivotally mounted adjacent said platen, a stop, a dog mounted on said arm, connections between said dog and said tripper whereby the dog 30 will be brought into operative engagement with said stop upon actuation of the tripper, and means for returning said dog to normal inoperative position.

7. In a safety device for addressing machines, the combination of a platen arm, a platen carried thereby, a tripper yoke pivotally mounted on said arm, a tripper pivoted to said yoke so as to be capable of movement relatively to said platen, a dog 40 mounted on the platen arm, a ratchet bar

disposed adjacent the arm, and operative connections between said tripper yoke and dog whereby the dog is brought into operative engagement with said ratchet bar to stop the movement of the platen arm upon 45 actuation of the tripper.

8. In a printing machine, the combination of a platen arm having a reciprocatory printing stroke, a platen mounted thereon, a tripper carried by the platen arm and adapted to engage with an obstruction in the path of the platen, and means actuated by said tripper to positively and instantaneously stop the printing stroke of the platen 50 arm.

9. In a printing machine, the combination of a platen arm having a reciprocatory printing stroke, a platen mounted thereon, a tripper carried by the platen arm and adapted to engage with an obstruction in the path of the platen, a stop and a dog mounted on the platen arm and actuated by said tripper to engage said stop to positively and instantaneously stop the printing 60 stroke of the platen arm.

10. In a printing machine, the combination of a frame, a platen arm pivotally mounted in said frame, a platen mounted thereon, a tripper carried by the platen arm and adapted to engage with an obstruction 70 in the path of the platen, a toothed bar mounted on the frame, and means actuated by said tripper to engage said bar to positively and instantaneously stop the printing stroke of the platen arm.
